[57] **CLAIM**

The ornamental design for a reconfigurable toy cassette, substantially as shown and described.

DESCRIPTION

FIG. 1 is a front elevational view of a reconfigurable toy cassette showing my new design;

FIG. 2 is a left side elevational view thereof;

FIG. 3 is a rear elevational view thereof;

FIG. 4 is a right side elevational view thereof;

FIG. 5 is a top plan view thereof;

FIG. 6 is a bottom plan view thereof;

FIG. 7 is a top plan view of the design shown in FIGS. 1 through 6 reconfigured in a humanoid condition;

FIG. 8 is a bottom plan view thereof;

FIG. 9 is a top plan view thereof;

FIG. 10 is a left side elevational view thereof;

FIG. 11 is a rear elevational view thereof; and

FIG. 12 is a right side elevational view thereof.
